UNITED STATES PATENT OFFICE.

MATTHEW SCHAMANN, OF ALMA, WISCONSIN.

SAWING-MACHINE.

1,109,252.

Specification of Letters Patent.

Patented Sept. 1, 1914.

Application filed June 2, 1913. Serial No. 771,233.

To all whom it may concern:

Be it known that I, MATTHEW SCHAMANN, a citizen of the United States, residing at Alma, in the county of Buffalo and State of Wisconsin, have invented certain new and useful Improvements in Sawing-Machines; and I do hereby declare the following to be a full, clear, and exact description of the invention, such as will enable others skilled in the art to which it appertains to make and use the same.

This invention relates to machines for sawing wood into short lengths, such as used for firewood; and it consists in the novel construction and combination of the parts hereinafter fully described and claimed.

In the drawings, Figure 1 is a side view of a sawing machine constructed according to this invention. Fig. 2 is a plan view of the same. Fig. 3 is a cross-section, taken on the line $x-x$ in Fig. 2. Fig. 4 is a section through one of the guides 3, taken on the line $y-y$ in Fig. 1.

The machine is provided with a supporting frame 2 of any approved construction, and two pairs of guides 3 and 4 for the saw holders 5 are secured to, or built into, the said frame. The saw holders 5 extend longitudinally in the guides, and their rear ends 30 are pivoted to the upper ends of levers 6 by pins 7. The lower ends of the levers 6 are pivoted to the frame by pins 8. A crank-shaft 9 is journaled in the frame and is provided with a handle 10 and a fly-wheel 11, or other suitable driving devices, for revolving it. Its cranks 12 are arranged at a right angle to each other, and are connected to the levers 6 by connecting-rods 13. The saw blades 14 are secured to the front ends of the saw holders 5. The front guides 3 have vertical chambers 15 in their uprights, and 16 are plungers which are slidable in the said chambers. A crossbar 17 is pivoted to the plungers 16 by pins 18 and projects 45 through slots in the uprights. The two saw holders rest on the tops of the plungers, which project above the tops of the chambers in which they are slidable vertically.

A hand lever 20 is pivoted by a pin 21 to one of the guides 3, and extends crosswise of the machine. A cord 21, or other flexible connection, is secured to the lever 20 at one

end, and passes over a guide sheave 22 at the top of the guides 3, and has its other end secured to the crossbar 17. A pin or stop 55 23 is provided on one of the guides 3 for the hand lever to engage with when depressed. This stop supports the saw blades in a raised position as shown, and when the lever is disengaged from the stop the saw 60 blades can descend upon the wood to be sawed.

Curved arms 25 are provided and are pivoted in bearings 26 on the top of the guides 3. The front ends of these arms 25 have 65 forked portions 27 which engage with the saw blades, and 28 are springs arranged between the arms 25 and the guides 3, and operating to press the saw blades downwardly.

A V-shaped, or channel-shaped, support 70 30 for the wood is provided, and is secured to the front part of the frame between the two saw blades. The middle part of this support has notches or slots 31 in its upper portion, and 32 is a retaining hook which 75 works in the slots 31 and hooks over the piece of wood placed in the channel of the support. The lower end of the hook 32 is pivoted to the crank 33 of a crankshaft 34 which is journaled in the frame. A lever 80 35 is secured to one end of the crankshaft 34 and affords a means for raising or lowering the hook 32.

The wood is held in the channel of the support by the hook which is depressed so 85 as to clamp it, and the saws are lowered onto the wood, and are reciprocated by means of the crankshaft 9. The saws are pressed on the wood by the springs 28, and as the crossbar 17 is pivoted to the plungers 90 90 and supported by a single cord, the saw blades balance each other to some extent in cutting.

The frame 2 is portable, and the machine can be moved from place to place. For this 95 purpose the frame is usually mounted on wheels or runners, which are not shown as they are of any approved construction.

What I claim is:

In a sawing machine, the combination, 100 with two guides provided with hollow uprights having slots in their adjacent sides, of two saws slidable in the guides above the hollow uprights, plungers for raising the

- saws slideable in the hollow uprights and projecting from their upper ends, a crossbar pivoted at its opposite ends to the two plungers and working in the said slots, and
5 means for raising the plungers simultaneously connected to the middle part of the crossbar.

In testimony whereof I have affixed my signature in the presence of two witnesses.

MATTHEW SCHAMANN.

Witnesses:

O. J. PAULSON,
JOHN MEILI.
